US0D1013684S

(12) **United States Design Patent** (10) Patent No.: **US D1,013,684 S**
(45) Date of Patent: ** Feb. 6, 2024

(54) **COMPUTING DEVICE**

(71) Applicant: **Microsoft Corporation**, Redmond, WA (US)

(72) Inventors: **Timothy G. Escolin**, Seattle, WA (US); **Jazmine Ama Hoyle**, Seattle, WA (US); **Byungkwan Min**, Kirkland, WA (US); **Ralf Groene**, Kirkland, WA (US); **Panos Costa Panay**, Redmond, WA (US); **Young Soo Kim**, Bellevue, WA (US)

(73) Assignee: **Microsoft Corporation**, Redmond, WA (US)

(**) Term: **15 Years**

(21) Appl. No.: **29/808,697**

(22) Filed: **Sep. 22, 2021**

(51) LOC (14) Cl. **14-02**

(52) U.S. Cl.

USPC **D14/345**

(58) **Field of Classification Search**

USPC D14/315, 342, 345, 346, 376, 432, 433, D14/439, 447; D8/323, 325; D18/12.2–12.3; D20/43

(57) **CLAIM**

The ornamental design for a computing device, as shown and described.

DESCRIPTION

FIG. 1 is a front perspective view of a computing device showing our new design;

FIG. 2 is a front view thereof;

FIG. 3 is a rear view thereof;

FIG. 4 is a right-side view thereof;

FIG. 5 is a left side view thereof;

FIG. 6 is a top view thereof; and,

FIG. 7 is a bottom view thereof.

The broken lines represent portions of the computing device that form no part of the claimed design.

1 Claim, 5 Drawing Sheets
